WINDOW SASH BALANCE

Algol Larson, New York, N. Y., assignor to Unique Balance Company, New York, N. Y., a corporation of Illinois

Application January 21, 1938, Serial No. 186,065

2 Claims. (CL. 16—197)

This invention relates to window sash balances of the general character of that shown in Letters Patent of the United States No. 2,041,646, dated May 19, 1936, granted to Unique Balance Company as the assignee of Algol Larson, in which each sash is counterbalanced by a coiled spring or coiled springs with which is associated a metal tube for the purpose of preserving the alignment of the spring or springs and in which in the movement of the sash there is more or less relative movement in contact as between the tube and the spring or springs. It has been found that in the operation of such window sash balances that in the movement of the sash there is some grating noise caused by the relative movement of the spring or springs and the tube in contact and some condensation of moisture on the surface of the tube, either internal or external, which tends to cause corrosion of the spring or springs. It is the object of this invention to provide means for deadening the sound and, as well, for absorbing such moisture and in accordance with the invention there is provided for such tube, either externally or internally or both, a lining, as of paper or other similar material, which in practical operation has been found to overcome the difficulties referred to.

In the drawing, in which the invention is illustrated—

Figure 1 is a view, partly in elevation and partly in section, of a window to which the invention is applied.

Figure 2 is a view in perspective of a strip of sheet metal, adapted for the formation of the tube, with the paper-like lining applied thereto, partly broken away.

Figure 3 is a cross-section of the same on a larger scale.

Figure 4 is a view in cross-section of a tube with the paper-like linings applied thereto.

Figure 5 is a detail view of the same in vertical section, the counterbalance springs and spiral being also shown, and

Figure 6 is a detail view similar to Figure 3, but showing the lining applied to both sides of the metal sheet from which the tube is formed.

The window frame, in which the present invention is to be embodied, may have as usual a head or lintel *a*, a jamb *a*¹ with a parting strip *a*² and a sill *a*³, the upper sash *b* and the lower sash *b*¹ being arranged to move vertically in the frame. For each upper sash and each lower sash there is provided at each side a counterbalance which, as fully explained in said Letters Patent, is connected to the respective sash, such counterbalance comprising an alining tube *c*, an internal torsion spring *d*, a long spiral member *e*, and an external supplemental extension spring *g*.

The alining tube *c* is formed of a metal strip *c*¹, which has secured to it, as by cement, before rolling, at one side, as shown in Figures 2 and 3, a lining sheet *c*² of paper or other similar material, or as shown in Figures 4, 5 and 6, at the other side also, a similar lining sheet *c*³. Tough paper is found to be a suitable material for the linings.

It will now be understood that such lining of the tube, whether internal or external, serves to deaden the sound due to the relative movement in contact of the adjacent internal spring or external spring or both, as the case may be, and serves also to absorb such moisture as may gather on the adjacent surface of the tube and so protect the spring or springs from corrosion.

I claim as my invention:

1. In a window sash balance, the combination of a counterbalance spring, and a metal spring-alining tube, the tube having adjacent the spring a lining of paper-like material whereby the sound of relative movement between the spring and the tube is deadened and provision is made for absorption of moisture.

2. In a window sash balance, the combination of a metal spring-alining tube, a torsional spring within the tube, and a tension spring outside the tube, the tube having on each side a lining of paper-like material whereby the sound of relative movement between the springs and the tube is deadened and provision is made for absorption of moisture.

ALGOT LARSON.
